UNITED STATES PATENT OFFICE

FRED L. MACKENZIE, OF BEVERLY, MASSACHUSETTS, ASSIGNOR TO UNITED SHOE MACHINERY CORPORATION, OF PATERSON, NEW JERSEY, A CORPORATION OF NEW JERSEY

WELT BUTTING AND TACKING MACHINE

Application filed March 29, 1928. Serial No. 265,704.

This invention relates to welt butting and tacking machines and is illustrated as embodied in a welt butting and tacking machine which is adapted to operate on shoes 5 having storm welts attached thereto.

The term "storm welt" refers to a welt which has a main portion similar to a usual welt and a bead portion which lies between the upper and the welt and serves to exclude 10 moisture from the welt crease and to give an attractive appearance to the shoe.

As affecting the operation of welt butting and tacking machines, storm welts are of two kinds. In one kind the bead is either 15 integral with the welt or is permanently attached to the welt prior to its being sewed to the upper and insole. In the other kind of storm welt the bead portion is separate from the main portion of the welt, which 20 may be a usual form of welt, the main portion and the bead portion of the welt, without previous attachment to each other, being fed through a suitable welt guide and both being attached to the shoe in the welting 25 operation. In this case, the ends of the welt and bead which extend beyond the ends of the inseam and with which the welt butting and tacking machine has to deal are therefore separate and unattached to each other. 30 For handling storm welts of the first kind above mentioned, the machine disclosed in United States Letters Patent No. 1,614,836 granted January 18, 1927, on application of George Goddu, is well adapted.

35 Objects of this invention are to provide an improved machine for performing the welt butting and tacking operation on shoes to which storm welts have been attached and particularly for operating on shoes having 40 storm welts of the second kind above mentioned attached thereto. A welt of this kind will, for the sake of brevity, be herein referred to by the term "two-piece storm welt" to indicate that the main portion and the 45 bead portion of the welt are not secured to each other prior to the welting operation.

50 Features of the invention consist in an organization comprising a welt support and an anvil plate for supporting the main portion of a storm welt, a ledge on the welt sup-

port to sustain the bead portion of the welt, and static means, that is, means which has no movement relatively to the welt support, for deflecting inwardly the end of the bead portion of the welt. Preferably, the deflection 55 of the bead is effected as a result of longitudinal rearward movement of the shoe incident to the positioning of the shoe in the machine. The illustrated machine is also provided with means for butting the main portion of the welt and with means for tacking 60 the inwardly bent bead portion of the welt, the machine being organized to operate upon both ends of the welt simultaneously.

It is desirable, in some instances, that the 65 end of the main portion of two-piece storm welting extend rearwardly beyond the bend of the bead portion and serve to close any crevice between the upper and outsole produced by the inwardly bent bead portion. Accordingly, in the illustrated machine the welt deflecting means comprises an inwardly directed portion on the welt support located forwardly of the guard or anvil plate which determines the line on which the main portion of the welt will be cut. The main portion of the welt will therefore extend rearwardly beyond the bend of the bead. Preferably, the inwardly directed portion of the 70 welt support is grooved to receive the bead portion and cause it to be bent inwardly as the shoe is pushed rearwardly with respect to it.

In other instances it is desirable that the 75 main portion of the welt be cut forwardly of the bend of the bead, and accordingly a construction is illustrated which may be used in place of that above referred to and in which the deflecting means is at the rear of the welt support and beneath the anvil plate so that the main part of the welt will be cut forwardly of the bend of the bead. In this construction provision is made for adjustment of the deflecting means transversely of the shoe to vary its bending effect.

In the drawings,

Fig. 1 is a front elevation of welt supporting, welt butting and tacking means provided at the left side of the machine illustrated as embodying the present invention;

Fig. 2 is a plan view of welt supports and side arms by which they are carried and showing a shoe in the machine after it has been operated upon;

Fig. 3 is a perspective view of one of the welt supports, bead deflectors and anvil plates with which the machine is provided;

Fig. 4 is a view, partly in section of one of the welt supports showing its relation to a shoe, the shoe being shown in section;

Fig. 5 is a view similar to Fig. 3 showing a shoe, partly broken away and in section, in its relation to the welt support, bead deflector, butting knife and tacking mechanism, the view being taken after the operation of the knife and prior to the tacking operation; and

Fig. 6 is a view similar to Fig. 3, showing a modified construction of the welt support, the deflector and the anvil plate.

The illustrated machine, which is especially designed for butting and tacking two-piece storm welting, is organized in general in the manner disclosed in application Serial No. 628,234, filed March 28, 1923, by Goddu and Mackenzie, to which reference may be had for explanation of parts not herein described in detail. As illustrated herein, the numeral 10 indicates a welt support at the left-hand side of the machine, and 12 one at the right-hand side of the machine. Each welt support has a welt engaging surface 14 which is inclined downwardly and inwardly with respect to a shoe being operated upon to cause the cut portion of the welt to receive the proper transverse taper. The welt support 10 (Fig. 3) is dovetailed into a supporting member 16 having a substantially horizontal surface 18 upon which a welt butting knife 20 travels in the welt butting operation. The surface 18 extends rearwardly of the welt support 10 to form a guard and anvil plate 22, the forward edge 24 of which determines the line on which the welt end will be cut, the bevel of the welt end being determined by the inclination, longitudinally and transversely of the shoe, of the welt supporting surface 14 with respect to the surfaces 18 and 22 which are substantially in a horizontal plane. The inner edge face of the welt support 10 is provided with a groove 26 to receive the bead portion of the welt. The lower side 28 of the groove constitutes a ledge for supporting the bead portion of the welt. At the upper side of the groove is a lip 30 which extends to a less distance transversely of the shoe than the ledge 28, as shown in Fig. 4, and helps to support the main portion of the welt. As shown in Fig. 6, however, this lip is not essential and the welt support may be provided simply with the bead supporting ledge 28. At its rear end the welt support 10 has a portion 32 with an inwardly and rearwardly directed edge face in which is formed a groove which, as

illustrated, may be a continuation of the groove 26 to constitute a bead deflecting means.

The member 16, which carries the welt support 10, is secured at 34 to a side arm 36 (Fig. 2) and it will be understood that a similar support 38 is attached to a side arm 40 at the opposite side of the machine, the support 38 carrying the welt support 12 which, of course, is provided with bead supporting and bead deflecting means, with a guard and anvil plate, and with a butting knife and tacking means similar to those described for the left-hand side of the machine and illustrated in Figs. 1, 3 and 5.

The side arms are connected for equal and opposite movement but are normally held apart by a spring 42 in such positions that a shoe may be introduced, as shown in Fig. 2, with the ends of the main portion of the welt lying upon the welt supporting surfaces 14 and with the bead portion supported by the ledges 28. As the shoe is moved rearwardly into the machine, the bead portions of the welt move along the grooves 26 and are deflected inwardly by the portions of the grooves in the inwardly extended portions 32 of the welt supports into the positions shown. In the operation of the machine the side arms 36, 40 are moved inwardly to hold the shoe tightly between the welt supports, the butting knives 20 acting in the plane of the surfaces 18 and 22 to butt the welt, and tackers 44 descend to force downwardly the deflected ends of the bead portion against the shoe bottom and to insert tacks 46 through the ends of the bead portion and into the insole of the shoe.

The showing of Fig. 5 is somewhat diagrammatic as to the butting knife 20 and the tacker 44. It is to be understood that the knife 20 first moves downwardly and then longitudinally and rearwardly of the shoe with its edge in the plane of the surfaces 18, 22 to butt the end of the main portion *a* of the welt, and that the tacker 44 then descends to press the inwardly bent end of the bead portion *b* of the welt and to insert a tack at the point indicated by the dotted numeral 46, the knife 20 at that time being located rearwardly beyond the tacker 44, which of course rises prior to the return movement of the knife, which first rises and then moves forwardly of the shoe in a plane parallel to but above that of its operative movement. In Figs. 4 and 5 the upper of the shoe is indicated by the character *c*, the insole by *d*, the last by *e*, and by *f* the stitches by which the main portion *a* of the welt, the bead portion *b* of the welt and the upper *c* are secured to the rib of the insole *d*.

In the construction shown in Figs. 3 and 5 it will be observed that the bend of the inwardly directed bead portion *b* of the welt is located forwardly of the shoe with respect

to the end of the main portion *a* of the welt which, after it is butted, is coincident with the edge 24 of the plate 22. The end of the main portion of the welt therefore extends 5 rearwardly beyond the bend of the bead portion of the welt and helps to fill any crevice produced by the location of the inwardly bent bead portions of the welt between the upper and the outsole.

10 In some instances, however, it may be desirable to have the end of the main portion of the welt terminate forwardly of the bend of the bead portion of the welt, and accordingly the construction shown in Fig. 6 is 15 provided. In this construction a welt support 50 has at the lower corner of its edge face a ledge 52 for supporting the bead portion of the welt. At the rear of the welt support 50 a member 54 is provided which is arranged 20 for adjustment transversely of the shoe and is provided at its inner end with a rearwardly and inwardly directed edge face 56 which is grooved to receive and deflect the bead portion of the welt inwardly of the shoe. 25 The edge 58 of an anvil plate 60, which determines the line at which the butted end of the welt would terminate, is located, in this construction, at the rear end of the welt support 50, and since the bead deflecting means 30 56 is located at the rear of the edge 58, the bend of the bead portion will extend rearwardly of the shoe beyond the butted end of the main portion of the welt.

Having thus described my invention, what 35 I claim as new and desire to secure by Letters Patent of the United States is:

1. In a welt butting machine, a welt support having means to support the bead portion of a two-piece storm welt, and means 40 for turning the end of the bead inwardly of the shoe as a result of longitudinal movement of the shoe relatively to said means.

2. In a welt butting machine for handling shoes having two-piece storm welting attached thereto, welt supports, and bead deflecting means constructed and arranged to cause the ends of the bead portion of the welt of a shoe to be bent inwardly of the shoe as a result of movement of the shoe longitudinally into the machine.

3. In a welt butting machine, a welt support having a ledge to support the bead portion of a two-piece storm welt, and means having a groove extending inwardly of the shoe to cause the end of the bead to be turned inwardly of the shoe by longitudinal movement of the shoe relatively to the welt support.

60 4. In a machine for operating on welt shoes having two-piece storm welting attached thereto, the combination of means for supporting one portion of the end of the welt, and static means for bending inwardly of the shoe the other portion of the welt end

as a result of longitudinal rearward movement of the shoe into the machine.

5. In a welt butting machine, welt supports having grooves to receive the bead portion of a two-piece storm welt, the rear portions of said supports extending inwardly of the shoe to cause the ends of the bead to be turned inwardly of the shoe by longitudinal movement of the shoe relatively to the welt supports.

70 6. In a welt butting machine for operating upon shoes having two-piece storm welting attached thereto, the combination of welt supports and bead supporting and guiding members constructed and arranged to cause the ends of the bead portion of the welt to be bent inwardly of the shoe as a result of movement of the shoe longitudinally into the machine.

75 7. In a welt butting machine for handling storm welting which comprises a main portion and a bead portion, the combination of welt supports to receive the main portion of the welt for the butting operation, said supports having ledges on their inner edge faces to support the bead portion of the welt, and static deflectors to bend inwardly of the shoe the ends of the bead portion of the welt.

80 8. In a welt butting machine for handling shoes having two-piece storm welting attached thereto, welt supports having upper faces to support the ends of the main part of the welt, ledges to support the ends of the bead portion, and members having inwardly and rearwardly inclined faces to turn inwardly the ends of the bead portion relatively to the shoe as a result of longitudinal movement of the shoe relatively to the welt supports.

85 9. In a welt butting machine for operating upon shoes having two-piece storm welting attached thereto, the combination of welt supports having upper faces to support the main portion of the welt ends and ledges to support the ends of the bead portion, and members having inwardly and rearwardly inclined faces which are grooved to receive the bead and which act to turn inwardly the ends of the bead portion relatively to the shoe as a result of longitudinal movement of the 90 shoe relatively to the welt supports.

100 10. In a welt butting machine for operating upon shoes having storm welts attached thereto, the combination of a welt support, an anvil plate on which the welt end lies to be butted, welt butting means arranged to operate in the plane of the upper face of the anvil plate to butt the welt, and a static deflector located below the anvil plate for turning inwardly the bead portion of the welt.

105 11. In a welt butting machine for operating on shoes having two-piece storm welting attached thereto, the combination of a welt support having a grooved edge to receive the bead portion of the welt, an anvil plate on 110

which the welt end lies to be butted, and a static deflector located in a plane below the upper face of the anvil plate for turning inwardly the bead portion of the welt.

12. In a welt butting machine for operating upon shoes having storm welts attached thereto, the combination of a welt support having a grooved edge to receive the bead portion of the welt of a shoe, an anvil plate 10 on which an end of the welt lies to be butted, welt butting means arranged to operate in the plane of the upper face of the anvil plate to butt the welt, and a deflector located in a plane below that of the upper face of the 15 anvil plate for turning inwardly the bead portion of the welt.

13. In a welt butting machine for operating on shoes having attached thereto storm welting which comprises a main portion and 20 a bead portion, the combination of means for supporting an end of the main portion of the welt for the butting operation, welt butting means, means for supporting an end of the bead portion of the welt, and a static deflector to bend inwardly of the shoe the 25 end of the bead portion of the welt.

14. In a welt butting machine for operating on shoes having attached thereto storm welting which comprises a main portion and 30 a bead portion, the combination of means for supporting an end of the main portion of the welt for the butting operation, welt butting means, means for supporting an end of the bead portion of the welt, and static means 35 constructed and arranged to bend inwardly of the shoe the end of the bead portion of the welt, the bend of the bead being located forwardly with respect to the shoe of the line on which the main portion of the welt is 40 butted.

15. In a welt butting machine for operating on shoes having two-piece storm welting comprising a main portion and a bead portion, the combination of welt supports to 45 receive the ends of the main portion of the welt for the butting operation, said supports having grooved inner edges to receive the bead portion of the welt, and static deflectors to bend inwardly of the shoe the ends of the 50 bead portion of the welt.

16. In a welt butting and tacking machine for operating on shoes having two-piece storm welting comprising a main portion and a bead portion, the combination of a welt 55 support constructed and arranged to sustain the main portion of the welt for the butting operation and having a ledge to support the bead portion of the welt, means fixed with 60 respect to the welt support for bending inwardly of the shoe the end of the bead portion of the welt which extends beyond the inseam, means for butting the main portion of the welt, and means for tacking the bead 65 portion to the shoe bottom.

17. In a welt butting and tacking machine for operating on shoes having storm welting attached thereto comprising a main portion and a bead portion, the combination of a 70 welt support constructed and arranged to sustain the main portion of the welt for the butting operation, means for butting the main portion of the welt, said supports having ledges to support the bead portion of the welt, means fixed with respect to the welt supports and located forwardly of the line 75 on which the main portion of the welt is butted for bending inwardly of the shoe the end of the bead portion of the welt, and means for tacking the bead portion of the 80 welt to the shoe bottom.

18. In a welt butting and tacking machine for operating on shoes having two-piece storm 85 welting comprising a main portion and a bead portion, the combination of welt supports to sustain the main portion of the welt for the butting operation, said supports having ledges to support the bead portion of the welt, means acting as a result of introduction of a shoe into the machine for bending 90 inwardly the ends of the bead portion of the welt, means for butting the main portion of the welt, and means for tacking the bead portion of the 95 welt to the insole.

In testimony whereof I have signed my 95 name to this specification.

FRED L. MACKENZIE.
